UNITED STATES PATENT OFFICE.

REESE B. KENT, OF WHEELING, WEST VIRGINIA.

MUSICAL INSTRUMENT.

1,322,795.

Specification of Letters Patent. Patented Nov. 25, 1919.

Application filed February 26, 1919. Serial No. 279,249.

To all whom it may concern:

Be it known that I, REESE B. KENT, a citizen of the United States of America, and resident of Wheeling, county of Ohio, and 5 State of West Virginia, have invented certain new and useful Improvements in Musical Instruments, of which the following is a specification.

This invention relates broadly to playing 10 mechanism for stringed instruments, and more particularly to a mechanical player for stringed instruments, associated with a player piano and actuated in conjunction with the latter by a traveling perforated 15 music-sheet.

The primary object of the invention is to provide in association with a player piano a mechanism whereby the strings of a 20 stringed instrument, as a violin, are sounded and fingered in synchronism with the playing of the player piano during the same time that such piano is played as ordinarily, such mechanism being operated under the 25 control of the same music-sheet by which the piano is played. In other words, it is aimed to so combine or connect a player piano and a violin-playing mechanism that both are adapted to be played in synchronism by a single specially cut note-sheet.

30 With these and other objects in view, the invention resides in the features which will hereinafter be described, reference being had to the accompanying drawings, in which—

Figure 1 is a front elevation of a cabinet- 35 contained violin and the playing mechanism associated therewith;

Fig. 2 is an enlarged rear elevation of the motor and shiftable friction-drive for the sounding or bowing mechanism;

40 Fig. 3 is a side elevation of the disk-depressing mechanism and of the means for controlling the pressure applied by the disks;

Fig. 4 is a top plan view of the disk- 45 driving and pressure-control mechanisms;

Fig. 5 is a cross-sectional view of the shutters, illustrating the shutter controlling means;

Fig. 6 is a side elevation of one of the 50 string-picking devices disclosed in Fig. 1;

Fig. 7 is a top plan view of one end of the clavier bar employed in the piano with which my invention is associated;

Fig. 8 is a view showing in perspective a

fragmentary portion of said clavier bar, 55 illustrating the application of said bar;

Fig. 9 is a view of an action lifter and the lower flange rail of a piano, showing the electrical contacts carried by said parts;

Fig. 10 is a front elevation of a fragmentary portion of the keyboard of a piano showing the push-button contacts whereby manual control of various parts of the stringed-instrument playing mechanism is afforded;

Fig. 11 is a diagrammatic view of the electrical system controlling the sounding mechanisms;

Fig. 12 is a diagrammatic view illustrative of the electric circuits controlling the 70 fingering devices.

Fig. 13 is a vertical section of a conventional form of player piano, partially illustrating the application of the invention thereto, portions of the player mechanism 75 being omitted; and—

Fig. 14 is a diagrammatic top plan view of the violin bowing and picking mechanisms.

Referring to said drawings, in which like 80 designating characters distinguish like parts throughout the several views—

1 indicates a cabinet or casing within which is contained a violin 2 or other similar stringed instrument. Located in proper 85 positions over the neck 2^a of the violin is a plurality of string-fingering devices having associated therewith electro-magnets 86 whereby they are actuated. Said magnet-actuated fingering devices are of a type well-known in the art and will consequently not be described herein.

90 Located within an end of the casing 1 adjacent to the butt-end of the violin is a transverse line shaft 3 carrying bevel-gears 4, said shaft being journaled in suitable bearings, as 5, and carrying at one end thereof a transmission disk 6.

A relatively smaller disk 7 located at right angles to said disk 6 is disposed with a point on its periphery in engagement with the outer flat face of the last-mentioned disk, so that the latter will be 95 frictionally driven through rotation of said disk 7.

Said disk 7 is carried by a sleeve 8 which is splined upon and longitudinally 100 shiftable along a drive-shaft 9 which is coupled to the shaft of a small electric motor 10.

The bevel gears 4, of which there are four, one for each string 11 of the violin, are respectively in mesh with similar gears 12 carried by the outer ends of shafts 13 which are disposed in overlying relation to said butt-end of the violin. Said shafts 13 are journaled adjacent to their outer ends in suitable bearings, as 14, and each thereof has fixed upon its opposite, or free, end a bowing-disk 15 adapted to be depressed during rotation thereof into engagement with an underlying string 11 of the violin for producing a sound in imitation of that produced by drawing an ordinary violin-bow 10 across such string. Said bowing-disks are continuously driven from the motor 10 through the intermediate mechanism described, but the speed at which they are driven may be varied by shifting the sleeve-carried disk 7 along the drive-shaft 9, it being obvious that the speed communicated to the transmission disk 6 will be increased as the disk 7 approaches its center, and vice versa. For effecting shifting movement of 15 said disk 7 along said shaft 9 I employ a shifting lever 16 having a shifter yoke 16^a at one end in operative relation to the sleeve 8 by which said disk is carried. Said lever is pivoted intermediate its ends upon a suitable support, as shown at 17 in Fig. 2, and is normally maintained by suitably arranged means as the retractile coil springs 18, in an intermediate position, or in a position wherein the disk 7 is held in engagement 20 with the face of disk 6 at an approximately midway point between the center and periphery of the latter. The said lever has a portion thereof disposed intermediate two opposed electro-magnets 19 and 20 in such position that it constitutes an armature adapted to be attracted by either magnet according as one or the other of the latter is energized. Said magnets are located in separate electric circuits, or in separate branches of 25 a single electric circuit, and are energized in a manner which will hereinafter be described.

The shafts 13 which carry the bowing-disks 15 are rendered flexible by forming 30 each thereof of two alined shaft sections connected by a slightly resilient flexible coupling, as a coil spring 21 of short length. Said disks are normally supported by said shafts 13 in elevated positions over the strings 11 of the violin, and they are individually depressible into operative relation to said strings through pressure applied to the front ends or sections of said shafts. The means employed for depressing said 35 disks to operative positions includes electrically actuated levers 22, one for each of said disks. Each of said levers is pivoted intermediate its ends upon a suitable support, as a standard 23. Said lever, which is normally held in a substantially horizontal po-

sition, as by means of a suitably located spring 85, has adjustably mounted on its front end a vertically disposed stem 24^a carried by a collar-like bearing 24 in which the forward section of the underlying shaft 70 13 is journaled. The rear end of said lever is of angular form, having a depending vertically disposed member 22^a provided with a forwardly directed terminal portion or lip 22^b which constitutes an armature for 75 an electro-magnet 25 that is suitably supported thereover, as shown in Fig. 3. When one of the magnets 25 is energized in a manner which will hereinafter be explained, the armature 22^b associated therewith is attracted thereby, resulting in the swinging of the lever 22 upon its pivot to a position wherein the thereby-controlled bowing-disk 15 is depressed into engagement with the 80 underlying string. 85

Each of the four magnets 25 is located in a normally open electric circuit which is closed by bringing a movable contact member 26 into engagement with a stationary contact member 27. Said contact members 90 may be located on any suitable parts of the piano action of any ordinary player piano, as 95, Fig. 13, so that they will be brought into contact for closing the electric circuit in which they are located by operative movement of one of said parts in the usual manner occasioned by the passage of a perforation in the traveling player-piano music-sheet 96 over the tracker-board 97. As shown for illustrative purposes in Fig. 9 of 100 the drawings, the stationary contact member 27 is mounted in a suitable position upon the lower flange rail 28 of the piano, and the movable contact member 26 is carried by the substantially-upright vertically-movable abstract 29 which is seated upon the rear end of the usual piano key 87 and which has pivotal connection with said lower flange-rail. Obviously, when the said abstract 29 is elevated in the usual manner, 105 the contact member 26 engages contact member 27. This effects the closing of an electric circuit in which said contact member and one of the electromagnets 25 are located and results in such magnet being energized. 110 115

Other normally-open electric circuits including the magnets 86 which control the fingering mechanisms for the violin are employed, one such circuit or a branch circuit 120 being provided for each of said magnets. However, since about forty-four fingering magnets are employed and an equal number of such electric circuits is required, all of which are substantially identical, but two 125 thereof are illustrated in the diagram shown in Fig. 12 of the drawings. Each circuit includes contacts 26' and 27', similar to the contacts 26 and 27 hereinbefore mentioned. The contacts 26' are carried by abstracts 29, 130

and the contacts 27' are carried by the lower flange-rail 28 in appropriate positions.

It may here be explained that any four of the piano keys and the actions directly associated therewith may be selected as those with which the said contact members 26 and 27 are used, and similarly any forty-four other keys and actions may be selected as those with which contacts 26' and 27' are used, such, however, being preferably keys located at the opposite ends of the keyboard and which may be most readily dispensed with in ordinary piano playing. As hereinbefore indicated, these keys will be actuated in the manner common to actuation 10 of the keys of a player piano, including perforations in the music-sheet used. The perforations used for actuating the four selected keys must, however, be specially cut to correspond with the notes which it is desired shall be produced by the violin—that is, the perforations must be so disposed on the sheet that the said four piano keys and their actions shall be actuated for closing the four electric circuits through the magnets 25 in the order and succession required to produce the desired notes resulting from movement of the bowing-disks into operative engagement with the violin strings. 20 And the perforations for actuating the forty-four, or other number of, fingering magnets selected must obviously be specially cut to produce properly timed fingering action of said magnets.

Located adjacent to the rear ends of the levers 22 is mechanism whereby the pressure applied through said levers to the shafts 13 carrying the bowing-disks 15, and, consequently, whereby the pressure of said disks upon the violin strings, may be controlled 30 or varied to the extent that the resultant sound may be rendered loud or soft. Said mechanism, which is under the manual control of the operator seated at the piano, includes a rock-shaft 30 journaled on suitable supports, as 31, and extending in a direction transverse to said levers. Fixed on said shaft 30 are four cams 32, one for each of said levers 22, said cams being designed to coöperate with the upper inclined 40 surfaces of rearward extensions 22' carried by the upright members 22^a of said levers to limit the extent of movement of the latter. Also fixed on said shaft 30 at a suitable point is one end of an arm 33 which 45 constitutes an armature for each of two oppositely disposed electro-magnets 34 and 35. Retractile coil springs 36 attached to the free end of said arm 33 serve to normally hold the latter in a position midway between said magnets 34 and 35, in which position the bowing-disk-carrying levers are permitted to swing to the extent that their disks 15 exert a medium, or normal, sounding pressure on the violin strings 11. When 55 the magnet 34 is energized, said arm 33 is thereby attracted and moved to an upwardly inclined position, effecting shifting of the cams 32 to positions permitting a maximum stroke of the levers 22 when the latter are actuated, and, consequently, producing a maximum of pressure of the actuated disk or disks upon the strings, resulting in the production of loud tones. A reverse movement of the arm 33, effected by energizing magnet 35, acts to swing the cams 32 to 60 positions wherein they serve to limit the stroke of the levers 22 to the extent that the bowing-disks, when actuated, will very lightly engage the underlying strings and produce a soft tone.

Said magnets 34 and 35 are located in separate manually closable electric circuits so as to be under the control of the operator. In view of the fact that it is desirable to accelerate the rate of speed at which a bowing disk is driven when the latter is caused to exert upon a string its maximum pressure for producing a loud tone, and to decrease the speed of such disk when a light pressure is exerted by the latter for producing a soft tone, the speed-control magnets 19 and 20 are respectively wired in series, or included in the same circuits, with said pressure-control magnets 34 and 35. Referring specifically to Fig. 11, magnets 19 and 34 are included in one side of a normally open electric circuit which comprises a battery 36 or other source of electrical energy, connected wires or conductors 37 and 38 leading from one pole of said battery to a contact-piece 100 composing a part of a manually closable switch 39 preferably of the push-button type, the other member of which is connected by a conductor 40 to said magnet 19 which is in turn connected by a wire 41 to 105 said magnet 34 whence connected wires 42 and 43 lead to the opposite pole of said battery. In like manner magnets 20 and 35 are included in one side of a normally open electric circuit consisting of said battery 36, connected conductors 37 and 44, the contact-pieces of a manually closable switch 45, conductor 46, magnet 20, conductor 47, magnet 35 and connected conductors 48 and 43. 110 From the foregoing it will be obvious that when the switch 39 is closed, magnets 19 and 34 are simultaneously energized, resulting in increasing above the normal rate the speed of the bowing-disks 15 and, at the same time, in permitting such disk-carrying levers 22 as are actuated during the interval in which said switch is closed to depress their disks to the greatest limit of which they are capable; also, that when the switch 45 is closed, 115 magnets 20 and 35 are simultaneously energized, resulting in decreasing below the normal rate the speed of the bowing disks and, at the same time, limiting the throw or stroke of such disk-carrying levers as are actuated during the interval in which said 120 magnet 35 is energized.

switch remains closed to the extent that their disks but lightly engage underlying strings of the violin.

Also illustrated diagrammatically in Fig. 11 are the four lever-actuating magnets 25, the four sets of closable contacts 26 and 27 and the four normally open electric circuits in which said magnets and sets of contacts are located, each of said circuits including 10 the battery 36, connected wires or conductors 37, 49 and 50 leading from said battery to stationary contact 27, a wire 51 leading from the movable contact 26 to one of the shiftable members of a four-point switch 52, a 15 wire 53 leading from a contact 54 with which said member is normally engaged to the magnet 25, and connected conductors 55 and 43 leading from said magnet to said battery.

20 Said four-point switch 52 is normally held, as by a retractile spring 56, in a position in which its four members engage the four contacts 54, rendering said circuits closable through movement of the contacts 26 25 into engagement with their companion contacts 27, as hereinbefore described. Said switch 52 is, however, arranged so as to be shiftable from its said normal position by the attraction of an electro-magnet 57, when 30 the latter is energized, exerted upon an armature, as 58, attached to said switch. Said magnet 57 is located in a normally open electric circuit which includes a manually closable switch 59 located in a position convenient to the operator seated at the piano. Said electric circuit includes the battery 36, connected conductors 37 and 60 leading from said battery to one of the contact members of said switch 59, a conductor 61 leading 35 from the other contact member of said switch 59 to said magnet 57, and connected conductors 62 and 43 leading from said magnet to the battery. When energized by the closing of the switch 59, the magnet 57 effects 40 the shifting of the four-point switch 52 from its said normal position to a position wherein its members are out of engagement with the contacts 54, rendering the circuits through magnets 25 unclosable, and 45 wherein said members engage contacts 63. Each of the said contacts 63 is connected by a conductor 64 to an electro-magnet 65 located in a normally open electric circuit which embraces the battery 36, connected 50 conductors 37, 49 and 50, contacts 26 and 27, wire 51, a member of said four-point switch 52, the contact 63 then engaged by said member, one of the conductors 64, a magnet 65, and connected conductors 66 and 43 leading 55 from said magnet 63 to said battery. The closing of a circuit through any one of said magnets 65, effected automatically by the elevation of the movable contact 26 into engagement with contact 27 in the manner 60 hereinbefore described during the time that

the circuit through switch-shifting magnet 57 is maintained closed, results in actuation of a picker-device designed to pick an underlying string of the violin, which device will now be described.

Each picker-device, of which there are four, one for each violin string 11, located side by side in a position in front of the violin bowing disks described, comprises a horizontal rod 67 which is stationarily 70 mounted on a suitable support 68 and which extends transversely of the violin to a point in overhanging relation to a string 11. A turnbuckle 69 or other appropriate means is provided whereby the reach of 75 said rod may be adjusted. Pivottally mounted intermediate its ends upon the front end of said rod 67 is a short lever 70 having its upper end pivotally connected to the front end of a longitudinally movable 80 rod 71 which is suitably supported above said rod 67 and which has an angularly disposed rear end 71^a constituting an armature for an electro-magnet 65. Said rod 71 is normally held in the retracted position 85 shown in Fig. 6 by means of a suitably arranged spring, as 72, and said magnet 65 and the armature 71^a are so disposed relatively that when said magnet is energized, 90 attracting said armature, said rod 71 is advanced longitudinally for actuating the lever 70 to cause a picker-finger 73 pivoted or hinged to the lower, or free, end of said lever to swing upward past the violin string with which it is associated and, in passing 95 said string, to produce a plucking action on the latter, as with a plectrum. As is obvious, the extent of retraction of the rod 71 is limited by adjustment of a set-screw 94 with respect to the armature 71^a.

100 The casing 1 is provided with suitable shutters whereby the volume of sound permitted to escape from the interior thereof may in large measure be controlled. Such shutters may be located in any appropriate 105 position, as in opposite ends of the casing, and are designed to be shifted to and from closing relation to an opening or openings in said casing by any appropriate means. As shown for illustrative purposes in 110 Fig. 5, a plurality of shutters 74 are disposed within or adjacent to an opening or passage 75 in the end of the casing. Inwardly directed arms 76 carried by said 115 shutters are connected to a vertically movable rod 77 which is normally held by a spring 78 in an elevated position in which it maintains said shutters in inclined passage-opening position, permitting sound emitted by the instrument to escape in large 120 volume through the opening 75. Said rod 77 carries an arm 79 which constitutes an armature for an electro-magnet 80 located in a normally-open manually-closable electric circuit. When said magnet is energized 125 130

by the closing of said circuit, the rod 77 is drawn downward against the tension of spring 78, thus shifting said shutters 74 to vertical passage-closing position, so that a 5 relatively small volume of sound, or muffled sound, is permitted to escape. Said electric circuit comprises the battery 36, connected conductors 37 and 81 leading from said battery to one of the contact-members of a 10 push-button switch 82, a conductor 83 leading from the other contact member of said switch to said magnet 80, and connected conductors 84 and 43 leading from said magnet to the battery.

15 The various push-button switches 39, 45, 59 and 82 providing for the manual control of the various mechanisms, as hereinbefore described, may occupy any appropriate positions but are preferably grouped 20 upon a suitable portion of the front part of the piano in a position within convenient reach of the operator of the player piano with which my invention is associated, as shown in Fig. 10.

25 As hereinbefore indicated, the violin bowing and fingering mechanisms described are designed to be actuated together with the player piano and by means of the same traveling perforated music sheet which 30 operates the player piano. Those keys of the piano which are associated with the violin bowing and fingering mechanisms are silenced by a clavier-bar 88 which is mounted upon the top of the usual hammer-butt spring-rail 89 of the piano, said 35 clavier-bar being shiftable from an out-of-the-way position on said spring-rail, indicated in dotted lines in Fig. 7, to an advanced position, shown in full lines in said 40 figure, wherein its front edge, which is felt-covered, as shown at 90, is adapted to be engaged by the shank 91 of the usual piano hammer 92 and thus to arrest such hammer at an intermediate point in its stroke for 45 preventing the hammer from striking the piano wire 93 with which it normally operates. As is obvious, any appropriate means may be employed for shifting said clavier-bar to and from its normal retracted 50 position. Said clavier-bar is designed to arrest only those hammers of the piano which are associated with the bowing and fingering mechanisms of the violin, or other stringed instrument, which hammers are 55 preferably those composing parts of key-actions, located at opposite ends of the piano key-board, which may be most readily dispensed with in ordinary piano playing, the bar being shaped to present an obstruction to full or complete movement of those 60 key-actions which are so utilized, as shown in Fig. 7, and to permit intermediate non-utilized key-actions to be actuated in the usual manner without interference. When 65 it is desired to manually play the piano, or

when it is desired to operate the piano player alone in the usual manner, utilizing the ordinary 88-note player roll or sheet, the battery 36 is disconnected to render the violin bowing and fingering mechanisms inoperative, and the clavier-bar 88 is shifted to its normal position to permit of unobstructed operation of the piano hammers 92.

70 What is claimed is—

1. The combination with a player piano 75 having its key-actions adapted to be actuated by a traveling perforated music sheet, of means for silencing some of said key-actions, a violin or other similar stringed instrument, a bowing device disposed adjacent to each of the strings of said instrument and including an electro-magnet, a plurality of fingering devices associated with said strings, each fingering device including an electro-magnet, a plurality of electric 80 circuits including the various electro-magnets mentioned, and circuit opening and closing devices comprising electrical contacts carried by relatively movable parts of silenced key-actions of the piano, such devices being actuated by operative movement of one of said parts occasioned through the provision of perforations in the music sheet.

90 2. The combination with a player piano having its key-actions adapted to be actuated by a traveling perforated music-sheet, 95 of means for silencing some of said key-actions, a violin or other similar stringed instrument, a bowing device disposed adjacent to each of the strings of said instrument and including an electro-magnet, a plurality of fingering devices associated with said strings, each fingering device including an electro-magnet, a plurality of electric 100 circuits including the various electro-magnets mentioned, and circuit opening and closing devices comprising electrical contacts carried by relatively movable parts of selected silenced music-sheet-controlled key-actions 105 of the piano.

110 3. The combination with a player piano adapted to be actuated by a traveling perforated music-sheet, of a violin or other similar stringed instrument, a bowing device disposed adjacent to each of the strings 115 of said instrument and including an electro-magnet, a plurality of fingering devices associated with said strings, each fingering device including an electro-magnet, a plurality of normally-open electric circuits including said electro-magnets, electrical contacts located in said circuits adapted to effect closing of the latter, said contacts being carried by relatively movable parts of selected music-sheet-operated key-actions of 120 the piano, and means for rendering said selected key-actions inoperative for piano playing while remaining key-actions remain operative for such playing.

125 4. The combination with a player piano 130

the key-actions of which are adapted to be actuated under the control of a traveling perforated music-sheet, of a violin or other similar stringed instrument, a bowing device disposed adjacent to each string of said instrument, means for actuating said bowing devices to move into operative engagement with said strings, said actuating means including an electro-magnet, a normally open electric circuit in which the last-mentioned magnet is located, electrical contact members in each of said electrical circuits, said contacts being carried by relatively movable elements of selected key-actions of the piano and being adapted to be carried into engagement for closing said circuits by operative movements of said selected key-actions, which movements are made responsive to perforations in said music-sheet, and means for resting said selected key-actions in their movements for rendering them inoperative for piano sounding, said means permitting the remainder of said key-actions to function for piano sounding responsive to other perforations in said music-sheet.

5. The combination with a player piano having its key-actions responsive to perforations in a traveling perforated music-sheet, of means for silencing some of said key-actions without wholly restraining responsive movement of the latter, an electrical contact member carried by a movable part of each of said silenced key-actions, a fixed electrical contact member adapted to be engaged by the first mentioned contact member, an electric circuit in which said contact members are located and adapted to be closed by interengagement of said members, a violin, a bowing device disposed adjacent to each of the strings of said violin and including an electro-magnet located in one of said electric circuits and energizable through closing of the latter for actuating a part of said bowing device to move into sounding relation to the adjacent string, and fingering devices associated with said strings, each fingering device including an electro-magnet located in one of said electric circuits and energizable through closing of the latter for actuating a part of the related fingering device to assume fingering relation to the adjacent string.

6. The combination with a player piano having its key-actions adapted to be operated under the control of a traveling perforated music sheet, of means for silencing some of said key-actions, a stringed instrument associated with said piano, bowing and fingering devices for the strings of said instrument, an electro-magnet for controlling each of said devices, electric circuits in which said magnets are included, and electrical contacts located in each of said circuits and carried by relatively movable parts of the silenced key-actions, whereby, upon actuation

of the latter, said circuits are closed for energizing said magnets.

7. The combination with a player piano having its key-actions adapted to be operated under the control of a traveling perforated music sheet, of means for silencing some of said key-actions, a stringed instrument associated with said piano, rotating bowing-devices associated with the strings of said instrument, means for depressing said bowing-devices into engagement with said strings, each individual depressing means including an electro-magnet, a normally-open electric circuit in which said magnet is included, and electrical contacts carried by relatively movable parts of the silenced key-actions and adapted to be interengaged by actuation of the latter, said contacts forming the terminals of said circuit.

8. The combination with a player piano having its key-actions adapted to be operated under the control of a traveling perforated music sheet, of means for silencing some of said key-actions, a stringed instrument associated with said piano, a plurality of bowing devices, each including an electro-magnet, adapted to be depressed into engagement with a string of said instrument for bowing such string, an electric circuit having branches, each branch including one only of said bowing device magnets, and electrical contacts forming the terminals of each of said branch circuits, said contacts being carried by relatively movable parts of certain of the silenced key-actions and adapted to be interengaged by actuation of the latter.

9. The combination with a player piano having its key-actions adapted to be operated under the control of a traveling perforated music sheet, of means for silencing some of said key-actions, a stringed instrument associated with said piano, a plurality of bowing devices, each including an electro-magnet, adapted to be depressed into engagement with a string of said instrument for sounding such string, an electric circuit having branches, each branch including one only of said bowing device magnets, electrical contacts forming the terminals of each of said branch circuits, said contacts being carried by relatively movable parts of certain of the silenced key-actions and adapted to be interengaged by actuation of the latter, and means for controlling the extent of depression of said bowing devices, said means including an electro-magnet and a manually closable electric circuit in which said magnet is located.

10. The combination with a player piano having its key-actions adapted to be operated under the control of a traveling perforated music-sheet, of means for silencing some of said key-actions, a stringed instrument associated with said piano, a plurality

- of bowing devices located adjacent to the strings of said instrument, each of said bowing devices including a rotary element adapted to be depressed into engagement with a 5 string of said instrument for sounding such string, and each of said bowing devices also including an electro-magnet, means for rotating said rotary elements, an electric circuit having branches, each branch including one only of said bowing-device magnets, 70 and electrical contacts forming the terminals of said branch circuits, said contacts being carried by relatively movable parts of certain of the silenced key-actions and adapted to be 75 interengaged by actuation of the latter, fingering devices associated with said strings, each fingering device including an electro-magnet, an electric circuit having branches in which the last-mentioned magnets are located, and electrical contacts carried by relatively movable parts of others of said silenced key-actions and forming the terminals of the last-mentioned branch circuits, said contacts being adapted to be interengaged by 80 actuation of the last-mentioned key-actions for closing said branch circuits to energize the magnets therein.
11. The combination with a player piano having its key-actions adapted to be operated under the control of a traveling perforated music-sheet, of means for silencing some of said key-actions, a stringed instrument associated with said piano, a plurality of bowing devices located adjacent to the 30 strings of said instrument, each of said bowing devices including a rotary element adapted to be depressed into engagement with a string of said instrument for sounding such string, and each of said bowing devices also including an electro-magnet, means for rotating said rotary elements, an electric circuit having branches, each branch including one only of said bowing-device magnets, 90 and electrical contacts forming the terminals of said branch circuits, said contacts being carried by relatively movable parts of certain of the silenced key-actions and adapted to be interengaged by actuation of the latter, fingering devices associated with said strings, each fingering device being located in a normally open branch electric circuit closable through actuation of another of said silenced key-actions and being 95 actuated through closing of such branch circuit, and manually controlled means for adjusting the extent of depression of the rotary elements of the bowing devices.
12. The combination with a player piano having its key-actions adapted to be operated under the control of a traveling perforated music-sheet, of means for silencing some of said key-actions, a stringed instrument associated with said piano, a plurality of bowing devices located adjacent to the strings of said instrument, each of said bowing devices including a rotary element adapted to be depressed into engagement with a string of said instrument for sounding such string, and each of said bowing devices also including an electro-magnet, means for rotating said rotary elements, an electric circuit having branches, each branch including one only of said bowing-device magnets, 100 and electrical contacts forming the terminals of said branch circuits, said contacts being carried by relatively movable parts of certain of the silenced key-actions and adapted to be interengaged by actuation of the latter, fingering devices associated with said strings, each fingering device being located in a normally open branch electric circuit closable through actuation of another of said silenced key-actions and being 105 actuated through closing of such branch circuit, and electrically actuated means for increasing and decreasing the extent of depression of the rotary elements of the bowing devices, said means including manually- 110 closable electric circuits.
13. The combination with a player piano having its key-actions adapted to be operated under the control of a traveling perforated music-sheet, of means for silencing some of said key-actions, a stringed instrument associated with said piano, a plurality of bowing devices located adjacent to the strings of said instrument, each of said bowing devices including a rotary element adapted to be depressed into engagement with a string of said instrument for sounding such string, and each of said bowing devices also including an electro-magnet, means for rotating said rotary elements, an electric circuit having branches, each branch including one only of said bowing-device magnets, 120 and electrical contacts forming the terminals of said branch circuits, said contacts being carried by relatively movable parts of certain of the silenced key-actions and adapted to be interengaged by actuation of the latter, fingering devices associated with said strings, each fingering device being located in a normally open branch electric circuit closable through actuation of another of said silenced key-actions and being 125 actuated through closing of such branch circuit, and manually controlled means for adjusting the extent of depression of the rotary elements of the bowing devices.
14. The combination with a player piano having its key-actions adapted to be operated under the control of a traveling perforated music-sheet, of means for silencing some of said key-actions, a stringed instrument associated with said piano, a plurality of bowing devices located adjacent to the strings of said instrument, each of said bowing devices including a rotary element adapted to be depressed into engagement with a string of said instrument for sounding such string, and each of said bowing devices also including an electro-magnet, means for rotating said rotary elements, an 130

electric circuit having branches, each branch including one only of said bowing-device magnets, and electrical contacts forming the terminals of said branch circuits, said contacts being carried by relatively movable parts of certain of the silenced key-actions and adapted to be interengaged by actuation of the latter, fingering devices associated with said strings, each fingering device being located in a normally open branch electric circuit closable through actuation of another of said silenced key-actions and being actuated through closing of such branch circuit, means for limiting the extent of depression of the rotary elements of said bowing devices, and means for shifting the position of said limiting means.

15. The combination with a player piano having its key-actions adapted to be operated under the control of a traveling perforated music-sheet, of means for silencing some of said key-actions, a stringed instrument associated with said piano, a plurality of bowing devices located adjacent to the strings of said instrument, each of said bowing devices including a rotary element adapted to be depressed into engagement with a string of said instrument for sounding such string, and each of said bowing devices also including an electro-magnet, means for rotating said rotary elements, an electric circuit having branches, each branch including one only of said bowing-device magnets, and electrical contacts forming the terminals of said branch circuits, said contacts being carried by relatively movable parts of certain of the silenced key-actions and adapted to be interengaged by actuation of the latter, fingering devices associated with said strings, each fingering device being located in a normally open branch electric circuit closable through actuation of another of said silenced key-actions and being actuated through closing of such branch circuit, means normally limiting the extent of depression of the rotary elements of said bowing devices for causing said elements to exert a medium pressure on the strings, and means for shifting the position of said limiting means.

16. The combination with a player piano having its key-actions adapted to be operated under the control of a traveling perforated music-sheet, of means for silencing some of said key-actions, a stringed instrument associated with said piano, a plurality of bowing devices located adjacent to the strings of said instrument, each of said bowing devices including a rotary element adapted to be depressed into engagement with a string of said instrument for sounding such string, and each of said bowing devices also including an electro-magnet, means for rotating said rotary elements, an electric circuit having branches,

each branch including one only of said bowing-device magnets, and electrical contacts forming the terminals of said branch circuits, said contacts being carried by relatively movable parts of certain of the silenced key-actions and adapted to be interengaged by actuation of the latter, fingering devices associated with said strings, each fingering device being located in a normally open branch electric circuit closable through actuation of another of said silenced key-actions and being actuated through closing of such branch circuit, interengaging elements normally limiting the pressure exerted upon the strings of the instrument by the rotary elements of the bowing devices, means for shifting one of said elements to permit the pressure exerted by said elements to be increased above normal, and means for shifting said one element to reduce the pressure exertable by said elements below normal.

17. The combination with a player piano having its key-actions adapted to be operated under the control of a traveling perforated music-sheet, of means for silencing some of said key-actions, a stringed instrument associated with said piano, a plurality of bowing devices located adjacent to the strings of said instrument, each of said bowing devices including a rotary element adapted to be depressed into engagement with a string of said instrument for sounding such string, and each of said bowing devices also including an electro-magnet, means for rotating said rotary elements, an electric circuit having branches, each branch including one only of said bowing-device magnets, and electrical contacts forming the terminals of said branch circuits, said contacts being carried by relatively movable parts of certain of the silenced key-actions and adapted to be interengaged by actuation of the latter, fingering devices associated with said strings, each fingering device being located in a normally open branch electric circuit closable through actuation of another of said silenced key-actions and being actuated through closing of such branch circuit, means normally limiting the extent of depression of the rotary elements of said bowing devices for causing said elements to exert a medium pressure on the strings of the instrument, means for shifting said limiting means in one direction to permit a greater depression of said elements, and means for shifting said limiting means in another direction to abnormally limit the depressing movement of said elements.

18. The combination with a player piano having its key-actions adapted to be operated under the control of a traveling perforated music-sheet, of means for silencing some of said key-actions, a stringed instrument associated with said piano, a plurality

of bowing devices located adjacent to the strings of said instrument, each of said bowing devices including a rotary element adapted to be depressed into engagement with a string of said instrument for sounding such string, and each of said bowing devices also including an electro-magnet, means for rotating said rotary elements, an electric circuit having branches, each branch including one only of said bowing-device magnets, and electrical contacts forming the terminals of said branch circuits, said contacts being carried by relatively movable parts of certain of the silenced key-actions and adapted to be interengaged by actuation of the latter, fingering devices associated with said strings, each fingering device being located in a normally open branch electric circuit closable through actuation of another of said silenced key-actions and being actuated through closing of such branch circuit, means normally limiting the extent of depression of the rotary elements of said bowing devices for causing said elements to exert a medium pressure on the strings of the instrument, means for shifting said limiting means in one direction to permit a greater depression of said elements, means for shifting said limiting means in another direction to abnormally limit the depressing movement of said elements, and means actuated simultaneously with increased and reduced depression of said elements for increasing and reducing, respectively, the speed of rotation of said elements.

19. The combination with a player piano having its key-actions adapted to be operated under the control of a traveling perforated music-sheet, of means for silencing some of said key-actions, a stringed instrument associated with said piano, bowing devices for the strings of said instrument, each of said bowing devices including an electro-magnet and a rotatable element depressible into engagement with a string of said instrument through energizing of said magnet, an electric circuit having branches, each branch having one of said magnets located therein, said branch circuits being closable by actuation of certain of said silenced key-actions for energizing the magnets therein, and means for adjusting the pressure applied by said rotating elements upon the strings.

20. The combination with a player piano having its key-actions adapted to be operated under the control of a traveling perforated music-sheet, of means for silencing some of said key-actions, a stringed instrument associated with said piano, bowing devices for the strings of said instrument, each of said bowing devices including an electro-magnet and a rotatable element depressible into engagement with a string of

said instrument through energizing of said magnet, an electric circuit having branches, each branch having one of said magnets located therein, said branch circuits being closable by actuation of certain of said silenced key-actions for energizing the magnets therein, means normally limiting the extent of depression of said rotating elements to cause the latter to engage the strings with a medium pressure, and means for shifting said means to permit a greater pressure to be exerted by said elements.

21. The combination with a player piano having its key-actions adapted to be operated under the control of a traveling perforated music-sheet, of means for silencing some of said key-actions, a stringed instrument associated with said piano, bowing devices for the strings of said instrument, each of said bowing devices including an electro-magnet and a rotatable element depressible into engagement with a string of said instrument through energizing of said magnet, an electric circuit having branches, each branch having one of said magnets located therein, said branch circuits being closable by actuation of certain of said silenced key-actions for energizing the magnets therein, means normally limiting the extent of depression of said rotating elements to cause the latter to engage the strings with a medium pressure, and means for shifting said means to further restrict depression of said elements.

22. The combination with a player piano having its key-actions adapted to be operated under the control of a traveling perforated music-sheet, of means for silencing some of said key-actions, a stringed instrument associated with said piano, bowing devices for the strings of said instrument, each of said bowing devices including an electro-magnet and a rotatable element depressible into engagement with a string of said instrument through energizing of said magnet, an electric circuit having branches, each branch having one of said magnets located therein, said branch circuits being closable by actuation of certain of said silenced key-actions for energizing the magnets therein, means normally limiting the extent of depression of said rotating elements to cause the latter to engage the strings with a medium pressure, means for shifting said means to permit a greater pressure to be exerted by said elements, and means for reducing the permitted extent of depression of said elements.

23. The combination with a player piano having its key-actions adapted to be operated under the control of a traveling perforated music-sheet, of means for silencing some of said key-actions, a stringed instrument associated with said piano, bowing devices for the strings of said instrument,

each of said bowing devices including a rotatable element, means constantly rotating said elements, an electro-magnet for each bowing device and adapted when energized 5 to depress one of said rotating elements into sounding relation to a string of said instrument, and an electric circuit having branches, each branch having one of said magnets located therein, said branch circuits being closable by actuation of certain 10 of said silenced key-actions for energizing the magnets therein.

24. The combination with a player piano having its key-actions adapted to be operated under the control of a traveling perforated music-sheet, of means for silencing some of said key-actions, a stringed instrument associated with said piano, bowing devices for the strings of said instrument, 15 each of said bowing devices including a rotatable element, means constantly rotating said elements, an electro-magnet for each bowing device and adapted when energized to depress one of said rotating elements 20 into sounding relation to a string of said instrument, an electric circuit having branches, each branch having one of said magnets located therein, said branch circuits being closable by actuation of certain 25 of said silenced key-actions for energizing the magnets therein, means for limiting the extent of depression of said rotating elements, said means normally permitting a medium pressure to be exerted by said 30 elements on the strings, energizable means for shifting said limiting means, and manually closable electric circuits in which said 35 energizable means are located.

25. The combination with a player piano having its key-actions adapted to be operated under the control of a traveling perforated music-sheet, of means for silencing some of said key-actions, a stringed instrument associated with said piano, bowing 40 devices for the strings of said instrument, each of said bowing devices including a rotatable element, means constantly rotating said elements, an electro-magnet for each bowing device and adapted when energized to depress one of said rotating elements 45 into sounding relation to a string of said instrument, an electric circuit having branches, each branch having one of said magnets located therein, said branch 50 circuits being closable by actuation of certain of said silenced key-actions for energizing the magnets therein, means for limiting the extent of depression of said rotating elements, said means normally permitting 55 a medium pressure to be exerted by said elements on the strings, energizable means for shifting said limiting means to further limit the extent of depression of said elements, a second energizable means for shifting 60 said limiting means to permit increased 65 in-

depression of said elements, and manually closable electric circuits in which the two energizable means are located.

26. The combination with a player piano having its key-actions adapted to be operated under the control of a traveling perforated music-sheet, of means for silencing some of said key-actions, a stringed instrument associated with said piano, bowing devices for the strings of said instrument, 70 each of said bowing devices including a rotatable element, means constantly rotating said elements, an electro-magnet for each bowing device and adapted when energized to depress one of said rotating elements 75 into sounding relation to a string of said instrument, an electric circuit having branches, each branch having one of said magnets located therein, said branch circuits being closable by actuation of certain 80 of said silenced key-actions for energizing the magnets therein, means for limiting the extent of depression of said rotating elements, said means normally permitting a medium pressure to be exerted by said 85 elements on the strings, energizable means for shifting said limiting means to further limit the extent of depression of said elements, a second energizable means for shifting said limiting means to permit increased 90 depression of said elements, manually closable electric circuits in which the two energizable means are located, and means actuated by closing of the last-mentioned 95 circuits for changing the speed of 100 rotation of said elements.

27. The combination with a player piano having its key-actions adapted to be operated under the control of a traveling perforated music-sheet, of means for silencing some of said key-actions, a stringed instrument associated with said piano, bowing devices for the strings of said instrument, each of said bowing devices including a rotatable element, means constantly rotating said elements, an electro-magnet for each bowing device and adapted when energized to depress one of said rotating elements 105 into sounding relation to a string of said instrument, an electric circuit having branches 110 each branch having one of said magnets located therein, said branch circuits being closable by actuation of certain of said silenced key-actions for energizing the magnets therein, means for limiting the extent 115 of depression of said rotating elements, said means normally permitting a medium pressure to be exerted by said elements on the strings, energizable means for shifting said limiting means to further limit the extent of depression of said elements, a second energizable means for shifting 120 said limiting means to permit increased depression of said elements, a manually closable electric circuit for each of said ener- 125 130
